UNITED STATES PATENT OFFICE

ROBERT W. IRWIN AND NICHOLAS BEKIUS, OF GRAND RAPIDS, MICHIGAN, ASSIGNEES
TO ROBERT W. IRWIN COMPANY, OF GRAND RAPIDS, MICHIGAN, A CORPORATION
OF MICHIGAN

END EXTENSION TABLE

Application filed January 19, 1925, Serial No. 3,324. Renewed October 7, 1929.

This invention relates to extension tables. It is a primary object and purpose of the present invention to provide a table wherein the main top is securely attached to the supporting under frame and is rigid therewith and under which, at each end, extension top sections may be housed when not in use, the same being capable of withdrawal and elevation into the same plane with the top and provided with means whereby, after such withdrawal and elevation, the extension top sections may be moved backward into abutting contact with the ends of the table top, there being provided in this manner an enlargement or extension of the surface of the table top. Each extension top section at each end of the table is operable independently of the other so that the top may be increased in size by the area of either one or both sections as may be desired. A further object of the invention is to provide a structure of this character which, while very economically made and of relatively simple structure, is especially practical and effective in its operation, one very desirable feature of the invention consisting in the secure or fixed relation of the main top to its supporting under structure.

Many other objects and purposes of the invention, together with novel construction and arrangements of parts for attaining the same, will appear as understanding of the invention is had from the following description taken in connection with the accompanying drawings, in which,

Fig. 1 is a longitudinal vertical section through the upper part of the table, one of the extension top sections being in outer operative position and the other in inner concealed or inoperative position.

Fig. 2 is a fragmentary under-plan view of the construction shown in Fig. 1.

Fig. 3 is a view similar to Fig. 1 showing one of the extension top sections drawn outwardly to its extreme limit, wherein it is tilted downwardly somewhat at its outer end, being thereafter elevated and moved backward so that its inner edge abuts against the end of the main table top.

Fig. 4 is a section similar to Figs. 1 and 3,

showing one of the end extension top sections partially withdrawn.

Fig. 5 is a transverse vertical section through the upper part of the table at one end thereof, the end extension top section being in upper operative position.

Fig. 6 is a similar transverse section through the middle portion of the table.

Fig. 7 is a fragmentary transverse section adjacent one corner of the table illustrating the position of the extension section slides in their lower inoperative position, and

Fig. 8 is a perspective view of the table, one end thereof being extended and with a portion broken away to illustrate the under construction used therewith.

Like reference characters refer to like parts in the different figures of the drawings.

The table main top 1 may be of any conventional construction and, preferably, is rectangular in outline. Underneath this top is the supporting structure comprising a rectangular frame having sides 2 and ends 3, at the corners of which posts 4 are secured. At the upper edge of each side 2 an elongated block 5 is permanently secured, on which the top 1 rests and to which it is securely connected, thereby leaving open spaces 6 at each end of the table between the under side of the top 1 and the upper edges of the sides 2 and 3 of the under frame.

A cross bar 7 is secured to and extends between the blocks 5 under the table top 1. A second cross bar 8 is located directly below the bar 7 extending between and being attached at its ends to supporting blocks 9 permanently secured to the inner sides of the sides 2 to the under frame. Each of the ends 3 at each end thereof is cut away at its upper side adjacent the posts 4, thereby providing relatively deep slots 10, which at their upper portions, are somewhat widened as indicated at 11; and a short metal bar 12 is attached to the upper edge of each end 3 of the under frame at one end extending over the widened slotted portion 11, this being best shown in Figs. 5 and 7. These bars 12 at their upper sides lie flush with the upper edges of the ends 3 of the under frame.

At each end of the table, an extension top

section 13 having a length the same as the width of the main top 1 is located. Two bars 14 are secured in spaced apart relation to the under side of each section 13, passing through the slots 10 in the ends 3, and toward their inner ends being formed with downwardly and inwardly inclined portions 15, from which ends 16 extend inwardly in a plane lower than the plane of the main bodies of the bars 14. A pin 17 is carried by each bar 14, extending laterally therefrom and on the opposite side of each bar 14 a somewhat elongated narrow block 18 is permanently secured as by screws or other suitable connections, being located on the bars 14 somewhat farther out than the pins 17.

One of these extension top sections 13 is mounted at each end of the table and in the inoperative position thereof is located under the table, being received in the open spaces 6 between the lower side of the table and the upper edges of the under frame sides and ends 2 and 3. The bars 14, attached to said sections, extend inwardly between the cross bars 7 and 8. On the lower bar 8, as shown in Fig. 6, guide blocks 8^a are attached at the upper side separating the bars 14 serving as guides therefor. With both of the extension top sections 13 under the main top a plain top is presented and the extension sections are out of sight and not noticeable.

If it is desired to enlarge the table top at either or both ends, either or both of the sections 13 may be moved outwardly. In the first part of its movement, the section 13 will move straight outward or until the inclined parts 15 of the bars 14 come to the cross bars 7 and 8, whereupon the extension section will tilt downwardly at a slight angle as indicated at Fig. 4. With continued outward movement the extension section 13 is moved outward beyond the end of the top 1 or until the stop pins 17 engage with the adjacent corner posts 4, as shown in Fig. 3. This is the outermost position of the extension top section, after it reaches this point, the section 13 is elevated until the upper edges of the bars 14 bear against the under side of the main top 1, whereupon the extension section 13 is moved back, the blocks 18 passing above the projecting ends of the metal bars 12. This inward movement continues until the inner edge of section 13 abuts against the end of the top 1. Blocks 18, resting upon the bars 12, serve to support the extended section 13 in a plane coincident with the plane of the main top 1 and the lower inner end portions 16 of the bars 14 are located between the cross bars 7 and 8 as shown in Fig. 1. While only one of the sections is shown extended, it is evident that both may be extended in the same manner if the top is to be further enlarged.

To retract the extension section 13 it is necessary merely to draw the same outwardly

from the position shown in Fig. 1 to that shown in Fig. 3, dropping the same downward, then moving the same inwardly whereupon the blocks 18 which pass under the projecting ends of the bars 12 through the widened portions 11 of the slots 10. This inward movement continues until the inner edge of the section 13 strikes against the end of the blocks 5.

The construction is very simple but exceedingly practical. The top 1 being permanently and rigidly secured to the under table structure is rigid at all times and does not change position, nor is it liable to become detached from the rest of the table. The operation to bring an end extension member outwardly into extended position is very simple as well as the reverse operation of retracting the same to inoperative position under the main table top. This construction has proved exceptionally satisfactory in practice.

While the drawings show the sections as movable outwardly at the ends of the table it is obvious that the table may be extended at its sides instead of the ends, as shown, using the same structure. Accordingly the term "end" is to be considered not as of specific and limited meaning but to have a broader significance. For example, when the extension sections are mounted to be moved outwardly from the longer sides of the table top such portions then become the ends of the table within the meaning of my invention and the meaning of the terms applied thereto in the claims. Accordingly the invention is not to be considered as limited to any particular specific disclosure made in the drawings but is to be considered as comprehensive of all forms of structure coming within such defined scope of the claims.

We claim:

1. In an extension table, a main top, an under supporting frame for the top to which said top is rigidly attached, there being an open space at an end of the table between said main top and the supporting frame, an extension top section adapted to be located within said open space when not in use, bars fixedly attached to said section slidably mounted on the supporting frame for outward movement whereby the extension top section may be moved outwardly beyond the end of the table, and interengaging means on the adjacent end of the supporting frame and on said bars for holding the extension top section in the same plane with the main top when said section is elevated and moved with said attached bars backward to bring its inner edge into abutting engagement with the end of the main top.

2. In an extension table, a supporting frame, a main top located over the supporting frame and rigidly connected thereto, there being an open space between an end portion

of the frame and said top, an extension top section adapted to be located within said open space when not in use, bars connected to the extension section and passing through openings in the end of the supporting frame whereby said extension top section is movably mounted for outward movement beyond the end of the main top, said openings in the end of the frame through which said bars 5 pass having a lateral enlargement, supporting members attached to the end of the frame extending into said enlargements of the openings in the end of the supporting frame, and blocks connected to the slideable bars passing 10 through said enlargement to said openings on outward movement of the extension top section and passing backwardly over the projecting ends of the supporting members when the extension top section is moved back into 15 abutting engagement with the end of the main top.

3. An extension table comprising a frame having spaced apart sides and ends, an end of the supporting frame having openings 25 therethrough which at their upper portions are laterally enlarged, supporting members attached to said end of the supporting frame having one end extending into and over the lateral enlargements of said openings, upper 30 and lower cross bars carried between the sides of the supporting frame, a main top located over the supporting frame and rigidly attached thereto, there being an open space between the under side of the main top and 35 the end portion of the frame, an extension top section adapted to be received in said open space when not in use, slidably mounted bars attached to the extension top section passing through said openings in the end of the supporting frame and between the cross bars, and 40 a narrower elongated block attached to each of said sliding bars adapted to pass under the supporting members on outward movement of the extension top section and over 45 said supporting members on elevation of the section and movement back to bring its inner edge into abutting engagement with the end of the main top.

4. In an extension table, a supporting frame 50 having spaced apart sides and ends, upper and lower cross bars extending between the sides of the frame, an end of the supporting frame being provided with openings having lateral enlargements at their upper portions, 55 supporting members attached to said end of the supporting frame and extending at one end into and over said lateral enlargements to said openings, a main top located above the supporting frame and secured thereto, 60 there being an open space between one end portion of the top and the corresponding end portion of the supporting frame, sliding bars passing through said openings in the end of the frame and between said cross bars, 65 said sliding bars adjacent their inner ends

turning downwardly and inwardly for a short distance and thence again inwardly, an extension top section connected to the outer end portions of the sliding bars adapted to be received in the open space between the main top and supporting frame, stops on the sliding bars engageable with the supporting frame to limit the outward movement of the extension top section when its inner edge has passed a distance beyond the end of the main top, and blocks attached to the slideable bars adapted to pass underneath said supporting members on outward movement of the extension top section and above said supporting members on elevation of said section and backward movement thereof to bring its inner edge into abutting engagement with the end of the main top.

5. An extension table comprising a supporting frame having sides and ends, spacing members rigidly connected to the sides of said supporting frame at and above the upper edges thereof and between their ends, a main top rigidly secured to said spacing members whereby open spaces remain between the main top and ends of said supporting frame beyond the ends of the spacing members, extension top sections adapted to be received in said open spaces, bars fixed to said top sections carried by the ends of said supporting frame for 85 slidably mounting the same for inward or outward movement whereby the sections may be moved outwardly beyond the ends of the main top and thereafter elevated into the same plane with the main top and moved backwardly to bring the inner edges into engagement with the ends of the main top, and means engaging with said bars when the extension top sections are moved backwardly 90 for supporting said extension top section in the same plane with the main top when thus moved back into abutting engagement therewith.

In testimony whereof we affix our signatures.

ROBERT W. IRWIN.
NICHOLAS BEKIUS.
